United States Patent

Des. 234,982
Patented Apr. 22, 1975

234,982

CAMERA CASE

Masakazu Tomatsuri, Tokyo, Japan, assignor to Nippon
Kogaku K.K., Tokyo, Japan

Filed Jan. 5, 1973, Ser. No. 321,223

Claims priority, application Japan Sept. 2, 1972

Term of patent 14 years

Int. Cl. D16—99

U.S. Cl. D87—5 E

FIG. 1

FIG. 2

FIG. 3

FIG. 4

FIG. 5

FIG. 1 is a front elevational view of a camera case embodying my new design;

FIG. 2 is a side elevational view as seen from the right of FIG. 1, the opposite side being a mirror image of the side shown;

FIG. 3 is a rear view;

FIG. 4 is a top plan view; and

FIG. 5 is a bottom plan view.

The broken lines in FIG. 5 indicate stitching.

I claim:

The ornamental design for a camera case, as shown and described.
